US0D1025364S

(12) **United States Design Patent** (10) **Patent No.:** **US D1,025,364 S**
(45) **Date of Patent:** **** Apr. 30, 2024**

(54) **DENTAL CURING LIGHT**

(71) Applicant: **Ultradent Products, Inc.**, South Jordan, UT (US)

(72) Inventors: **Dee Jessop**, West Jordan, UT (US);
Jared Wayne Sheetz, Orem, UT (US);
Neil Thomas Jessop, Sandy, UT (US)

(73) Assignee: **ULTRADENT PRODUCTS, INC.**,
South Jordan, UT (US)

(**) Term: **15 Years**

(21) Appl. No.: **29/838,847**

(22) Filed: **May 16, 2022**

Related U.S. Application Data

(63) Continuation of application No. 17/693,536, filed on Mar. 14, 2022, which is a continuation of application No. 16/861,440, filed on Apr. 29, 2020, now Pat. No. 11,273,021, which is a continuation of application No. 13/133,129, filed as application No. PCT/US2009/069738 on Dec. 29, 2009, now Pat. No. 10,646,315.

(57) **CLAIM**

The ornamental design for a dental curing light, as shown and described.

DESCRIPTION

FIG. 1 is an upper perspective view of a dental curing light showing our new design;

FIG. 2 is a lower perspective view thereof;

FIG. 3 is an enlarged upper perspective view thereof, with the environmental subject matter removed for ease of illustration;

FIG. 4 is an enlarged lower perspective view thereof;

FIG. 5 is an exploded enlarged lower perspective view of a head portion thereof; and,

FIG. 6 is an enlarged lower perspective view of the head portion of FIG. 5;

The broken lines in the drawings are included for the purpose of illustrating portions and environmental elements of the dental curing light and form no part of the claimed design.

1 Claim, 4 Drawing Sheets
